UNITED STATES PATENT OFFICE.

LUCY PRESTON BROWN, OF ST. LOUIS, MISSOURI.

GRADUATED COPYHOLDER GUIDE.

Application filed October 17, 1921. Serial No. 508,317.

To all whom it may concern:

Be it known that I, LUCY PRESTON BROWN, a subject of the King of Great Britain, residing at St. Louis, Missouri, have invented 5 a new and useful Improvement in Graduated Copyholder Guides, of which the following is a full, clear, and exact description, such as will enable others skilled in the art to which it appertains to make and use the same, reference being had to the accompanying drawings, forming part of this specification, in which—

Figure 1 is a front elevation of a copyholder, showing my improved graduated 15 copy-holder guide strip in position.

Figure 2 is a front elevation of the upper part of a typewriter.

Figure 3 is a side elevation of my improved graduated copy holder guide strip. 20 The object of my invention is to provide a graduated guide strip to be placed on the horizontal cross bar or line guide of a copy-holding device to aid the copyist in accurately placing figures or wording on the paper 25 placed in the typewriter, the exact place or degree recorded by my graduated guide on the copyholder.

With these objects in view, my invention 30 consists in the construction, arrangement, and combination of the several parts of my device, all as will be hereinafter described and afterwards pointed out in the claim.

In the drawing (1) indicates a copyholder plate of a well-known type now generally used by copyists, which is manually 35 operated up and down. (2) is a stationary horizontal plain surfaced line guide bar in connection with the copy-holder to aid the copyist in pointing out the line upon which

she is working. (3) is my improved graduated strip, which is movable horizontally and supported on the stationary line guide bar (2). (4) is a column of figures on letter (5) and (5¹). (5¹) is a sheet of paper wound around roller (6) on typewriter (7). (8) 40 45 is a well-known stationary graduated strip that is on every typewriter.

By the use of my improved movable graduated strip fastened to the plain stationary line guide bar of a copy-holder, it will be 50 seen that a big saving in time and greater accuracy is effected, because the typist can set my graduated strip to correspond with the same graduation on the type-writer. For instance, a copy of figures to be copied stands 55 at 30 degrees on my graduated strip, as shown in drawing. It is a very simple matter, therefore, to place the typewriter scale in a similar position. Beginning of sentences, addresses, signatures, etc., can be set 60 in like manner, saving time and producing more accurate work, by the aid of the movable graduated strip.

I am aware that minor changes in the construction, arrangement, and combination, of 65 the several parts of my device can be made and substituted for those herein shown and described without in the least departing from the nature and principle of my invention.

Having thus described my invention, what I claim as new and desire to secure by Letters Patent is:

An attachment for a line marker of a copy holder comprising a graduated guide strip, 75 adapted to yieldably engage the line marker.

LUCY PRESTON BROWN.
